A. C. EASTWOOD.
APPARATUS FOR BREAKING AND TRANSPORTING IRON PRODUCTS.
APPLICATION FILED NOV. 7, 1905.

926,691.

Patented June 29, 1909.

UNITED STATES PATENT OFFICE.

ARTHUR C. EASTWOOD, OF CLEVELAND, OHIO.

APPARATUS FOR BREAKING AND TRANSPORTING IRON PRODUCTS.

No. 926,691.

Specification of Letters Patent.

Patented June 29, 1909.

Application filed November 7, 1905. Serial No. 286,186.

To all whom it may concern:

Be it known that I, ARTHUR C. EASTWOOD, a citizen of the United States, residing at Cleveland, in the county of Cuyahoga and State of Ohio, have invented or discovered new and useful Improvements in Apparatus for Breaking and Transporting Iron Products, of which the following is a specification.

My invention relates to a new and useful combination of devices for breaking up and handling products of iron or steel which it is desired to remelt or otherwise treat. These products may be in the form of skulls as they are called, which are composed of steel or iron which accumulates on the inner lining of ladles which have been filled with the molten metal, castings which have come from the sand in imperfect condition, worn-out machinery which has been scrapped, etc.

In the past this material has been broken up by what is commonly known as a skull cracker, which consists of a tripod fifty to seventy-five feet high, arranged at the top of the structure with a sheave, over which passes a hoisting cable. The free end of the cable is provided with a hook which may be tripped by means of a rope. This hook engages an eye in a heavy weight which is hoisted by means of a suitable engine attached to the cable. When the weight has reached the requisite height, it is tripped by the operator who pulls the rope attached to the hook. The weight is thus released and falls on the casting or other scrap which is thereby broken. This is a very slow and expensive process as the tripod is stationary and the point at which the weight may strike is therefore a fixed point. The aim of the weight is also frequently destroyed by the pull on the rope required to release the trip. Frequently also the weight in striking will roll over in such a way that the hook or eye in the weight will not be in an accessible position for attaching the hook again, necessitating the work of several men to turn over the weight so that the hook may be attached. Inasmuch as weights as high as twenty thousand pounds are frequently employed, this becomes a very tedious and expensive matter. Further, when the castings have been broken up, the broken pieces are usually gathered up by hand and loaded into cars.

My device may be used to break articles of any nature, whether of magnetic material or not, or to drop weights for other purposes than the breaking of articles.

With my improved apparatus when used in its preferable form, all hand work is eliminated in handling the scrap and placing it at the proper point in attaching the weight to the hoist, in releasing the weight from the hoist to cause it to drop and in gathering up the broken pieces and reloading them into suitable cars or receptacles. The weight is released in such a manner that there is no tendency to destroy its aim by causing it to swing. A single operator can conveniently operate the entire apparatus with convenience and dispatch and a number of men are dispensed with in what may be considered a very dangerous occupation inasmuch as accidents due to flying pieces of metal are very numerous with the ordinary form of skull cracker now in use.

My arrangement consists, in its preferable form, of an overhead crane, traveling upon a runway of suitable height, and being preferably of standard form, permits free motion in three directions, namely, the bridge of the crane travels horizontally along the runway, the trolley which carries the hoisting mechanism travels horizontally on the bridge of the crane transversely of the direction of travel of the bridge, and the hook attached to the hoisting cables or chains, of course, travels vertically. By this arrangement the hoist of the crane covers practically all of the space under the runway.

I attach to the hook of the crane an electro magnet, preferably of the form described in United States Patent No. 794,086 issued to me, July 4th, 1905. This magnet is used for unloading the scrap or castings from the railroad cars and suitably placing them on the ground. The weight which I employ for breaking the castings is preferably spherical in shape, and being thus symmetrical, it makes no difference whether or not it turns over or rolls to one side, as it always represents a face of the same contour to the poles of the magnet. The magnet which I prefer to use is concave on its lower face and therefore adapted to engage with spherical surfaces. The crane is equipped with a flexible electrical cable for conveying current to the magnet as it is moved about by the crane and the operator is provided with a switch by means of which the magnetizing circuit of the magnet may be closed and opened. The magnet is lowered upon the weight, the circuit closed, the weight hoisted slightly and the crane so moved that the weight is poised

directly over the metal which it is desired to strike. The weight is then hoisted vertically to its full height and the circuit of the magnet is opened. The weight is instantly released and drops down upon the metal to be broken. After the scrap or castings are broken, the magnet is used for gathering up the broken pieces and loading them into cars. The operator is at such a height above the ground that in ordinary cases he is not exposed to the danger of flying pieces of metal and in any event he can readily be protected by placing suitable screens around his cab.

15 It will readily be understood that by the arrangement above described a large amount of labor which is necessary with other devices is dispensed with and at the same time the risk of accident to workmen is very materially reduced.

20 The form of crane which I have above described is preferable for the work. However, what is known as a Gantry crane could be used which has a suitable bridge member carried by suitable shear legs which are provided with trucks and run upon rails on the ground. The bridge member, of course, is provided with the usual trolley which carries the hoisting mechanism across the bridge. A swing-35 ing or jib crane can also be used for the purposes described and the magnet could with considerable advantage also be applied to the stationary form of tripod skull cracker.

Referring to the drawing which forms a 35 part of this specification, Fig. 1 is an elevation illustrating one of the many ways in which my invention can be embodied; Fig. 2, a modification of Fig. 1 showing a second method of taking up the slack of the conductor cable; and Fig. 3, sectional view and end elevation of one way in which the conductor cable may be attached to the winding drum and the collector rings.

In the accompanying drawing A is the 45 bridge of an electric overhead traveling crane, which is propelled by motor A¹ along rails A², A², which are carried on suitable runways supported by columns A³, A³.

A trolley B is adapted to be propelled 50 across the bridge A by means of a suitable electric motor B¹ geared to the track wheels running upon suitable rails, as R, carried by the bridge member in the usual manner. The trolley is provided with a second electric 55 motor B² which is connected through suitable gearing with a hoisting drum B³. The drum B³ is supplied with a suitable cable B⁴ for hoisting the load. Electric current is supplied to the crane by sliding contacts V co-60 acting with the stationary trolley wires X, Y, mounted along the crane runway.

Suitable controllers (not shown) are placed 65 in the operator's cab C for operating the various motors on the crane. There is also contained within the operator's house a

small switch or controller K, which controls the circuit of a magnet M attached to the crane hook B⁵. In ordinary cases a simple switch only is required for closing and opening the circuit of the magnet. Where a high 70 voltage is used, however, I prefer to open the circuit of the magnet through a resistance as by means of a controller K, thereby reducing the inductive discharge at the time of final opening of the circuit. Current is 75 supplied to the magnet through the twin conductor cable M³ composed of the two conductors M¹, M².

Suitable trolley wires X¹, Y¹, which are not shown in their proper relative position, 80 are employed for transmitting current for energizing the magnet M. One end of the conducting cable M³ is mechanically attached to the winding drum D (see Fig. 3) and the two conductors M¹, M² are connected 85 electrically with two insulated collector rings D² and D³ carried on the shaft D¹ of the drum D. Suitable stationary contacts of brushes D⁴ and D⁵ coöperate with these collector rings for the purpose of supplying current to 90 the magnet while the drum D is rotating. Suitable sliding or rolling contacts X² and Y² coat with the trolley wires X¹, Y¹ and are in turn connected by the wires X³ and Y³ to the brushes D⁴ and D⁵ on the winding 95 drum D.

W is a steel ball or weight which is used for breaking up the material to be broken. This material may be conveniently delivered in railroad cars which pass under the 100 bridge of the crane. The skulls, castings, or metallic pieces to be broken are unloaded by means of the magnet M and placed in the desired position on the ground. The weight W is then brought into play as hereinbefore 105 explained and dropped upon the castings or other articles to be broken from a suitable height to properly break them. The broken pieces are then gathered up by means of a magnet M and loaded either into the same 110 cars or into other cars or conveyors provided for the purpose.

Referring now to Fig. 2 the cable M³ passes over the sheave F, and is looped over the sheave F¹, the loop F² carrying the traveling 115 sheave F³, to which is secured the weight F⁶, which serves in an evident manner to keep the cable tight, as the magnet is raised and lowered.

Having described my invention, I claim— 120

1. In combination in a device for breaking articles below the same, a drop-weight to break the articles, a hoisting device, a magnet attached to said hoisting device and adapted to lift said weight upon actuation of 125 the hoisting device, a sufficient distance to cause the weight, when released, to fall upon and break said articles and means for causing said magnet to release said weight.
2. In combination, a drop-weight, a mag- 130

net adapted to lift said weight a sufficient distance to cause the weight, when released, to fall upon and break an article below the same, a traveler to move said magnet horizontally, and means for causing said magnet to release said weight.

3. In an apparatus for breaking and transporting magnetic products, a traveler having horizontal movement, a hoisting device thereon, an electro-magnet attached to the hoisting device and adapted to attract to itself magnetic articles to be transported to

a convenient place to be broken and to be carried away after they have been broken, a drop-weight adapted to be lifted by said magnet and hoisting device and released so as to fall upon said articles and break the same.

Signed at Cleveland O, this 4th day of November, 1905.

ARTHUR C. EASTWOOD.
